WILLIAM H. BURNS, OF GRAFTON, ASSIGNOR TO JONATHAN LUTHER, OF WORCESTER, MASSACHUSETTS.

Letters Patent No. 99,287, dated February 1, 1870.

IMPROVEMENT IN ROLLER-JAW TEMPLE FOR LOOM.

The Schedule referred to in these Letters Patent and making part of the same.

To whom it may concern:

Be it known that I, WILLIAM H. BURNS, of Grafton, county of Worcester, Commonwealth of Massachusetts, have invented a new and improved Roller-Jaw Temple for Looms; and I do hereby declare that the following is a full and exact description thereof, reference being had to the accompanying drawings, and to the letters of reference marked thereon, making a part of this specification.

This invention is an improvement on my patent, issued September 28, 1869. In that device, it will be seen I make use of two grooved rollers, running together.

My improvement consists in the use of a grooved concave shell, or a grooved flat shell or surface, in connection with a grooved roller, or with a toothed roller, arranged to move laterally on its arbor. I make the teeth of the roller or rollers which run in the grooves in the shell, or in the grooved flat shell or surface, either plano-concave, fig. 3, or concavo-convex, as seen in fig. 5.

For heavy woolen cloth, I find the grooved flat shell or surface works much better than a grooved curved shell, as thick, heavy cloth will not yield and render through the curve of the shell, but is held securely by the grooved or toothed roller, and the straight grooved shell or flat surface.

When the grooved flat shell or surface is used, two rollers, side by side, running in the grooves, are better than one, (see fig. 6,) and one may be a grooved roller, and the other toothed, or both alike toothed or grooved.

The grooved rollers are mounted on their arbors so that they may vibrate laterally.

The grooved flat shell or surface has bars in front, between and back side of the rolls, and these bars prevent the cloth from going too deep in the grooves. The rollers are mounted on arbors, with room to revolve, and, as heretofore stated, vibrate or slide laterally thereon, so that the play will allow the cloth to be drawn in between the grooves of the roller and the grooves of the curved shell, or of the grooved flat shell or surface.

As the lay is carried forward, and the cloth slackened, the roller moves outward, and the cloth is drawn through between the grooves by the take-up of the loom; as the lathe moves back, the cloth tightens, and the roller moves inward, which closes the grooves on the cloth, clamping and holding it securely extended widthwise as the reeds leave it. Thus the grooves are opened and closed with each forward and backward movement of the lathe. The shape of these grooves, and also of the teeth, is new for this purpose; and by reason of such construction, the cloth has more room to pass between and be held by the edges of the grooves or teeth, which do not wedge down on the cloth like

the bevel groove, nor do the concavo-convex teeth penetrate the cloth like sharp teeth or spurs.

I construct a swing-stand, for attaching temples to the breast-beam of the loom. This device serves to give motion to the temple, at the forward and backward movements of the lathe, and at the same time to raise and lower the temple, thus conforming to the motion of the cloth, which is produced by the action of the harnesses and the lathe, hereinafter more fully described.

In the accompanying drawings—

Figure 1 is a perspective view of my roller-jaw temple and swing-stand together.

Figure 2 represents the grooved shell H, in the bed-piece of the temple.

Figure 3 represents the grooved roller B.

Figure 5 represents the toothed roller L.

Figures 6 and 7 represent the straight grooved flat shell or surface, and with rollers applied.

Figure 4 represents the swing-stand, detached from the temple.

To enable others skilled in the art to make and use my invention, I will proceed to describe its construction and operation.

It may be made of gray, cast, or malleable iron.

In fig. 1, letter A represents the adjustable part of the temple, which is made oval, the inner surface being hollowed out smooth, with an arbor passing through, as seen at J.

On this arbor is placed the grooved roller B, or the toothed roller L, having room to revolve, and also move laterally thereon.

Screw h fastens the piece A to the bed-piece C, and screw e regulates the jaws to the thickness of the cloth.

Letter C, as seen in figs. 1 and 2, represents the bed-piece of the temple, in the shell of which, at H, are cut the grooves, which are concaved, and formed so as to clamp the cloth on the edges of the grooves.

Letters e e, on part C, figs. 1 and 2, represent slots, for the screws a a. These two screws fasten the temple to that part of the swing-stand marked I, and it is thereby regulated.

Letter M, in fig. 7, represents the grooved flat shell or surface, and fig. 6, the rollers mounted on arbors, running in connection with the straight grooves. I have shown these rollers with the caps off; but caps may be applied, as in the case of the smooth shell in fig. 1. The toothed roller is made by first cutting the concavo-convex grooves, and then cutting transverse grooves, slightly spiral, and reversed on the arbors, so that the teeth bear on the cloth on the convex side. The grooved roller is made as heretofore explained.

The swing-stand is made in two parts, hinged together, as seen at G. (See figs. 1 and 4.)

On the part of the stand lettered I E, is cast an ar-

bor for a spiral spring, as seen at F. I do not confine myself to the spiral spring and arbor, as the only means by which the swing-stand may be operated. In some cases, it may be used without any spring. I use the spiral, or its equivalent, or no spring at all.

That part of the stand marked K, consists of two projections, or brackets, between which the spring is placed. These brackets are slightly curved on the upper edges, and admit of opening and closing the stand.

The edge also serves as a stopper, as it comes in contact with flange I, at f f.

The part of the stand marked D, has a flange, with slot d, for fastening the temple and stand to the breast-beam of the loom. I can use my temple by attaching it to the loom in various ways. I do not confine myself to this swing-stand as the only means of operating my temple; but I do consider this stand has a more perfect action than any of the other arrangements in use.

By attaching the stand to the breast-beam of the loom, with screw-bolt, at slot d, as seen in fig. 1, and regulating the temple for drawing the edges of the

cloth through between the jaws and the grooves, it is ready for operating.

As the lathe of the loom strikes that part of the swing-stand marked E, as seen in figs. 1 and 4, the temple is moved forward, and slightly raised, thus conforming to the movement of the cloth, produced by the action of the harnesses and the lathe.

Having thus described my temple and swing-stand, What I claim as my invention, and desire to secure by Letters Patent, is—

1. A temple, having a grooved shell jaw, in combination with a roller, or rollers, mounted on their arbors to move laterally, and when grooved and toothed, all as and for the purposes described.

2. The swing-stand, in combination with temples for looms, when constructed as and for the purposes herein described.

W. H. BURNS.
